DISCHARGE DUCT ASSEMBLY FOR
DEHYDRATORSWallace L. McGehee, Kansas City, Mo., assignor
to McGehee Company, Kansas City, Mo., a cor-
poration

Application November 4, 1946, Serial No. 707,729

5 Claims. (Cl. 34—136)

1.

This invention relates generally to dehydrating equipment of the kind having a rotatable, cylindrical drum disposed horizontally and adapted to remove moisture from comminuted material as the same is lifted and fed back by the drum into hot gases approaching the outlet port thereof.

More specifically this invention has to do with a discharge duct assembly for such dehydrators, and has for its primary aim the provision of means for positively controlling the moisture content of the material passing through the outlet port, by the employment of an adjustable tube telescoped in the outlet port, which tube is shiftable outwardly and inwardly with respect to the rotatable drum to the end that the moisture content of the escaping material is decreased or increased respectively.

The most important object of this invention is to provide in a discharge duct assembly for dehydrators having the aforesaid adjustable tube as a part thereof, a hollow shell communicating with the outlet port of the rotatable drum for slidably supporting the tube in telescoping relation therewith, whereby the tube may be moved into the drum to selected positions in accordance with the degree of moisture content desired in the dried material leaving the dehydrator through the tube.

Other objects of this invention include the manner of providing manually operable structure for shifting the tube from the exterior of the shell; the way in which the tube is held against movement from the selected position by the employment of a braking device, also operable from a convenient place on the shell; and the manner of constructing the parts of the assembly for attaining all of such objects as well as for attaining many minor objects which will be made clear during the course of the following specification, referring to the accompanying drawings, where-

in:

Figure 1 is a side elevational view of a discharge duct assembly for dehydrators made in accordance with my present invention, showing the same in association with a portion of a dehydrator drum.

Fig. 2 is a cross-sectional view taken on line II—II of Fig. 1.

Fig. 3 is a detailed enlarged, sectional view showing the manner of securing the shoe to its actuating screw.

Fig. 4 is a cross-sectional view taken on line IV—IV of Fig. 2.

Fig. 5 is a fragmentary, cross-sectional view taken on line V—V of Fig. 1; and

2.

Fig. 6 is a fragmentary top plan view of the shell, per se.

The drying of feeds such as alfalfa and the dehydration of other substances capable of being comminuted in the process of drying as the same is entrained in a stream of travelling air, may be controlled through the employment of the discharge duct assembly shown in the drawings.

The cylindrical drum 10 may take any of a number of forms, and is usually divided into a number of compartments, including a preheating chamber, a main drying compartment, a secondary drying compartment, a back-feeding section, etc. As the drum 10 rotates, a plurality of lifters not here shown but located along the inner walls of the drum cause the material to be dropped through a blast of hot gases traversing the drum 10 and leaving the same through an outlet port 12 formed in the end wall 14.

Only a portion of the back-feeding section of drum 10 is shown in Figs. 1 and 4. In the instances shown, a number of inclined vanes 16 cause a counter-flow of such material as will lie against the wall of the rotating drum for further passage through the hot gases. Other back feeding means may be used without altering the function of the adjustable discharge duct. The assembly about to be described governs the amount of heavier particles or those having a higher moisture content, that will pass from the dehydrator without being returned toward the center of the drum 10 by vanes 16.

Any suitable means may be used to rotate drum 10 and as such action takes place, external annular tracks 18 ride in flanged rollers 20, rotatably mounted on supporting foundations 22. For a more complete disclosure of the above-mentioned construction with which the structure hereof is adapted to be used, reference is had to my U. S. Letters Patent 2,470,315, dated May 17, 1949.

A hollow, cylindrical shell 24 extends outwardly from drum 10 and communicates with outlet port 12 through overlapping flanges 26 and 28 on shell 24 and end wall 14 respectively. If desired, these flanges may be made in sections and formed to slidably interlock as drum 10 rotates and shell 24 remains stationary.

Suitable framework for supporting the shell 24 takes the form of a pair of spaced uprights 30, braced by tie-bars 32, upon which a pair of gusset plates 34 are secured by bolts 36. The plates 34 have their uppermost edges arched to conform to the contour of the shell 24, and these plates 34 are welded or otherwise attached as

at 38 to an annular flange 40 on shell 24. When so supported, shell 24 is in axial alignment with outlet port 12, and has its longitudinal axis on a plane with the axis of rotation of drum 10.

A discharge tube 42 is slidably telescoped within shell 24 for axial, longitudinal movement to and from any number of predetermined positions where one end thereof extends through outlet port 12 and into drum 10. During such movement, tube 42 rides on a plurality of rollers 44, carried by pins 46, and extending into the shell 24 through openings 48 formed through the wall thereof and near its lowermost side. These rollers 44 are disposed in pairs, spaced apart to form a supporting cradle for the tube 42.

An elongated slot 50 is formed in the wall of tube 42 near the top thereof for receiving a gear 52 in mesh with a rack 54 which hangs from the inner face of tube 42 in alignment with slot 50 by brackets 56 fixed to tube 42. A down-turned flap 58 guides the material through tube 42 past rack 54, and the teeth of rack 54 are plugged as at 60 to limit inward movement of tube 42.

A bracket 62 secured to the outside of shell 24 mounts a number of bearing blocks 64 for journalling a shaft 66 upon which is mounted a gear 52 and an adjusting hand wheel 68. Openings 70 and 72 in bracket 62 and shell 24 respectively receive the gear 52 for engagement with the rack 54.

An arcuate shoe 74, disposed within the shell 24 above the tube 42, has a block 76 welded to the upper face thereof, which block 76 is provided with a cavity 78 to receive one end of an adjusting screw 80. This screw 80 has an annular groove 82 rotatable on a holding pin 84 in block 76 as torque is applied thereto.

A head 86 attached to the outer face of shell 24, has an internally threaded bore 88 for receiving screw 80, which bore 88 communicates with a cavity 90 in head 86, disposed to receive block 76 as the latter moves upwardly through opening 92 in shell 24. A hand wheel 94 on the upper end of screw 80 provides actuating means therefor.

As the dehydrator is placed in operation, the tube 42 is moved inwardly or outwardly with respect to drum 10 by turning wheel 68. As the tube 42 is moved outwardly to dispose a lesser amount of its length in drum 10, the material escaping from the dehydrator is drier than when the tube 42 is moved inwardly to the position shown in Figs. 1 and 4. As tube 42 is moved inwardly from the position shown, the material passing from the dehydrator has a higher moisture content. When the operator has set the tube 42 at the position desired, according to the extent of drying of the material which he has selected, actuation of wheel 94 will force shoe 74 downwardly against tube 42, which in turn is against rollers 44 to hold the same in place.

The original moisture content of materials will vary, as well as the desired condition of the finished product, therefore, since minute changes are possible in the assembly, the dehydrator will be greatly increased in efficiency by attachment of the structure above described.

Manifestly discharge duct assemblies for dehydrators may be made in varying forms of construction without departing from the spirit of this invention or scope of the appended claims.

Having thus described the invention, what is claimed as new and desired to secure by Letters Patent is:

1. A discharge duct assembly for dehydrators

of the kind having a cylindrical drum mounted for rotation about a horizontal axis, and provided with an outlet port through one end thereof, said assembly comprising a stationary hollow shell in communication with said outlet port and extending outwardly from the drum; a discharge tube slidably telescoped within said shell for movement to and from predetermined positions extending into the drum through said outlet port, said outlet port having a diameter greater than the outside diameter of the tube to permit free rotation of the drum relative to the tube; and means in the shell for holding the tube out of contact with the edges of said drum end forming the outlet port.

2. A discharge duct assembly for dehydrators of the kind having a cylindrical drum mounted for rotation about a horizontal axis, and provided with an outlet port through one end thereof, said assembly comprising a hollow shell in communication with said outlet port and extending outwardly from the drum; a discharge tube slidably telescoped within said shell and said outlet port for movement to and from predetermined positions extending into the drum; a rack fixed to the tube and extending longitudinally therewith; a gear rotatably mounted on the shell, said shell having an opening formed therein, said gear extending through the opening in meshing relation with the rack; and manually manipulable means for rotating the gear, whereby sliding movement is imparted to the tube.

3. A discharge duct assembly for dehydrators of the kind having a cylindrical drum mounted for rotation about a horizontal axis, and provided with an outlet port through one end thereof, said assembly comprising a stationary hollow shell in communication with said outlet port and extending outwardly from the drum; a discharge tube slidably telescoped within said shell for movement to and from predetermined positions extending into the drum through said outlet port, said outlet port having a diameter greater than the outside diameter of the tube to permit free rotation of the drum relative to the tube; and means in the shell for holding the tube out of contact with the edges of said drum end forming the outlet port, said means including rollers in the shell underlying the tube, there being at least one roller on each side of a vertical plane through the longitudinal axis of said tube.

4. A discharge duct assembly for dehydrators of the kind having a cylindrical drum mounted for rotation about a horizontal axis, and provided with an outlet port through one end thereof, said assembly comprising a hollow shell in communication with said outlet port and extending outwardly from the drum; a discharge tube slidably telescoped within said shell and said outlet port for movement to and from predetermined positions extending into the drum; a plurality of rollers mounted in the shell below said tube for supporting the tube as it is moved into and out of the drum; an arcuate shoe disposed between the shell and the tube in opposed relation to the rollers; and manually manipulable means attached to the shoe and extending through the wall of said shell for forcing the shoe against the tube whereby the tube is held against the rollers in any one of said positions.

5. A discharge duct assembly for dehydrators of the kind having a cylindrical drum mounted for rotation about a horizontal axis, and provided with an outlet port through one end there-

75

of, said assembly comprising a stationary hollow shell in communication with said outlet port and extending outwardly from the drum; a discharge tube slidably telescoped within said shell for movement to and from predetermined positions extending into the drum through said outlet port, said outlet port having a diameter greater than the outside diameter of the tube to permit free rotation of the drum relative to the tube; and means in the shell for holding the tube out of contact with the edges of said drum end forming the outlet port, said means including rollers in the shell underlying the tube, there being at least one roller on each side of a vertical plane through the longitudinal axis of said tube, and releasable structure on the shell overlying said tube for holding the tube against the rollers.
